UNITED STATES PATENT OFFICE.

JOHN H. WILSON, OF BALTIMORE, MARYLAND.

HEAT-STORING ATTACHMENT FOR STOVES.

1,382,585.

Specification of Letters Patent. Patented June 21, 1921.

Application filed August 8, 1918. Serial No. 248,941.

To all whom it may concern:

Be it known that I, JOHN H. WILSON, a citizen of the United States of America, residing at Baltimore, in the county of 5 Baltimore city and State of Maryland, have invented new and useful Improvements in Heat-Storing Attachments for Stoves, of which the following is a specification.

The object of the invention is to provide 10 in connection with heating stoves, a heat storing means located within the stove and above the heat producing element thereof to insure the retention of the heat, so that the heat may be given off gradually on any re- 15 duction of the heat from the fire, such as lowering the fire or decreasing the fuel supply thereof.

The invention accordingly consists in the 20 features of construction, the combination of elements and the arrangement of parts which will be exemplified in the construction hereinafter described and the scope of the application of which will be indicated in the appended claim.

25 The invention is clearly illustrated in the accompanying drawings, in which:

Figure 1 is a vertical sectional view of the 30 invention applied to a heating stove.

Fig. 2 is a horizontal section on the line 2—2 of Fig. 1.

Fig. 3 is another horizontal section taken on line 3—3 of Fig. 1.

Fig. 4 is a perspective view of the heat 35 containing element.

Similar characters of reference are employed in all of the above described views, to indicate corresponding parts.

Referring now, more particularly, to the 40 accompanying drawings, there is provided a stove consisting of a body 1 which may be and preferably is supported in spaced relation to a main supporting surface through the instrumentality of legs 2. The body is closed at the bottom while arranged with- 45 in the body slightly above the bottom is the heating means 3 which may be a gas burner, a coal oil burner, etc. A top 4 is mounted on the stove and may be and pref- erably is formed with perforations 5 which 50 serve as heat outlets while the walls of the body in proximity to the body are also perforated to provide other heat outlets 6.

With a view of providing improved means 55 for insuring the storing or retention of heat in the heating zone of the body of the stove, a heat containing element constructed in

the form of a disk 7 is formed desirably of soapstone and is carried against the under surface of the top and is also perforated as at 8 to provide heat passages which align 60 with the heat outlets 5. Carried against the inner surface of the walls or body of the stove near the cover are a series of suitably spaced bars 9 which act as heat retainers being preferably formed of soapstone. Co- 65 operating with the disk 7 is a heat conducting member 10 which is desirably in the form of a disk and made of copper being incidentally formed with perforations 11 which align with the perforations 8 to al- 70 low some of the heat to pass from the stove. The purpose of the copper disk is to serve as a conductor for quickly absorbing the heat which rises from the heating means and this disk is capable of imparting 75 or conducting heat to the soapstone disk in which the heat is stored or retained to permit of the lowering of the fire without materially decreasing the temperature or heat rising from the stove. The soapstone disk 80 thus acts as a fuel saver. For a similar purpose the bars 9 are provided with heat conducting coverings 12 also formed of copper.

It is believed in view of the foregoing de- 85 scription that a further detailed description is entirely unnecessary. Likewise, it is thought that the advantages of the invention will be readily apparent.

Having thus fully described this invention, what is claimed as new and desired to 90 be secured by Letters-Patent, is:

The combination with a stove having a hollow body, of a burner disposed within the stove near the bottom thereof, a per- 95 forated top closing the body at the upper end, a soapstone disk provided with per- forations aligning with the perforations in the top, the said disk lying against the lat- 100 ter and being disposed therebeneath, a cop- per disk lying against the soapstone disk and formed with perforations registering 105 with the perforations in the soapstone disk, and a plurality of soapstone bars vertically positioned and disposed around the interior surface of the body adjacent to the top and covered with copper, whereby the heat from the burner is communicated to the soapstone disk and bars to be gradually dispensed by the latter, as herein shown and specified.

In testimony whereof I affix my signa- 110 ture.

JOHN H. WILSON.
